UNITED STATES PATENT OFFICE.

ALEXANDER M. PASNIK, OF NORWICH, CONNECTICUT.

NAILBRUSH.

Application filed February 18, 1926. Serial No. 88,982.

This invention is an improvement in nail-brushes of the type disclosed in my Patent No. 1,568,569 of January 5, 1926, comprising a flat guide-bar and a separate brush member having a narrow back with bristles on one edge, said back being adapted to be slipped rearward on the guide-bar into the engagement and support of studs or the like. The object of the present invention is to provide an improved construction having certain advantages in respect to neatness, strength and general effectiveness.

In the accompanying drawings forming part hereof:—

Fig. 1 is a face or elevational view of the complete improved device;

Fig. 2 is a rear edge view of the same;

Fig. 3 is a face or elevational view of the brush member removed; and

Fig. 4 is a cross-section through the complete device, on a larger scale.

One part of the device comprises a flat guide-bar 2 having its opposite ends 3 incurved to fit the thumb and finger of the hand holding it. On one face of this bar, in the corner regions at the ends and rear edge are low abutments 4 of substantial cross-sectional area, and connecting these abutments and extending lengthwise over the rear portion of this face of the guide-bar is a relatively narrow retainer strip 5, narrowly spaced from said face. The elements 2, 4 and 5 may be made in separate pieces suitably united together, but the construction lends itself well to molding in a single piece of pyroxylin or like composition, and, it will be apparent, is of a sturdy character.

The separate brush member shown by itself in Fig. 3 comprises a thin, flat back 6, considerably narrower than the guide-bar 2, having a row of bristle tufts 7 along its front edge. The construction and relation are such that the back 6 will slip rearward closely between the bar 2 and the strip 5, against the rearward support of the abutments 4. For the latter purpose, the ends

8 of the back 6 are formed with hooks, horns or notches, in a suitable manner, substantially as shown. When the brush member 50 is thus inserted into position, the bristles 7 terminate back of the forward edge of the guide-bar 2, leaving a margin of such bar to serve as a guide for the finger nails.

In use, the brush member is held in place 55 by the rearward pressure of the nails pressing the back 6 against the abutments, and at other times by a sufficient amount of friction to keep the brush member from slipping out. Such friction may be between 60 the faces of the back 6 and the opposed faces of the bar 2 and the strip 5, or between the ends of the back 6 and the abutments, or it may be produced by the lateral pressure 65 of the resilient bristles themselves against the face of the bar 2.

What is claimed as new is:—

1. A nail-brush comprising a guide-bar having abutments on one face at its ends and rear edge, and a retainer strip extending between said abutments and narrowly spaced from the face of the bar, and a separable brush member comprising a thin back with bristles on one edge thereof, said back being removably positioned between the 70 guide-bar and the retainer strip with its ends against said abutments.

2. A nail-brush comprising a flat guide-bar, a retainer strip extending longitudinally over the rear portion of one face of said 80 bar, from which the retainer strip is narrowly spaced, and a separate brush member comprising a thin back with bristles on one edge thereof, said back adapted to be slipped rearward between the guide-bar and the retainer strip, and means connecting the strip and guide bar limiting inward movement of said brush back when so inserted, the construction and relation being such that lateral pressure of the bristles against 85 the face of the guide-bar produces friction for keeping the brush member in place.

ALEXANDER M. PASNIK.
